TIE HANGER

Laurence W. Van Dusen, Escondido, Calif., assignor to Mission Industries, Escondido, Calif., a corporation of California

Filed Jan. 17, 1966, Ser. No. 641

Term of patent 14 years

(Cl. D80—8)

FIG. 2 is an elevational view taken from one side thereof; and

FIG. 3 is an elevational view taken from one end thereof.

The broken line representation of ties in FIGURES 2 and 3 are for purposes of illustration.

I claim:

The ornamental design for a tie hanger, as shown and described.
